CLOSURE MEMBER

Nathan Zepelovitch, New York, N. Y., assignor to
Nauman A. Bernstein, New York, N. Y.

Application May 1, 1950, Serial No. 159,270

6 Claims. (Cl. 215—37)

1

This invention relates to closure members and particularly to a simple and efficient hermetically sealing closure member for containers, such as jars and bottles.

Conventional closure members for jars and bottles are usually restricted to use with a bottle or container of particular dimensions and are seldom adaptable for use with containers of differing dimensions. Some of the conventional closure members are relatively difficult to remove from the container mouth, particularly those of the screw-on type which are limited to use with a container of definite dimensions and thread contours and oftentimes become bonded to the container through solidified deposits of the material contained therein, particularly where the contained material is of a sugary nature. Although this type of closure member may be reused, the occasional difficulties of removal, together with its limitations as to container dimensions, are objectionable. Another common type of closure member is that which is crimped on the container mouth, or deformed into sealing engagement with the container or bottle, such as the conventional bottle cap for carbonated beverages. Although this type of closure member provides an adequate seal, it is difficult to remove, requiring the use of a special tool, and once removed it seldom, if ever, may be used again for sealing purposes. This type of cap is also limited to use with containers and bottles of particular mouth dimensions.

This invention may be briefly described as a simple internally gripping closure member adapted for use with containers of varying dimensions and mouth configurations that may be easily placed into and removed from hermetic sealing relationship in a simple and efficient manner. The closure member includes a supporting structure carrying a deformable sealing membrane and having a pair of angularly disposed extendible retaining arms, adapted for internal gripping of the container, passing through and attached to said membrane. The closure member is adapted to be placed into operative hermetically sealing relationship with the mouth of a container or bottle by manual depression of the retaining arms, against the restoring action of the membrane, into retaining position which is maintained by a frictional gripping of the retaining arms by the supporting structure. The closure member is adapted to be easily removed from hermetic sealing relationship by manual depression of a portion of the supporting structure.

Among the advantages of the improved clo-

2

sure member is that removal of the container does not require any turning or prying, and the insertion and removal of the closure member into and from hermetic sealing relationship is accomplished in a rapid, simple and efficient manner. The closure member also provides a sealing surface of relatively large magnitude and is readily proportioned for use with such varied shaped containers such as narrow necked carbonated beverage bottles and wide mouthed mason type jars.

An object of this invention is the provision of an improved hermetically sealing closure member for containers and bottles.

Another object of this invention is the provision of an improved closure member that may be used with containers and bottles of varying dimensions and mouth configurations.

Another object of this invention is the provision of an improved closure member that may be repeatedly reused for hermetic sealing purposes.

Another object of this invention is the provision of an improved closure member that may be easily and simply inserted into and removed from hermetic sealing relationship with a container or bottle mouth.

A further object of this invention is the provision of a closure member that is simple and inexpensive in construction.

Other objects and advantages of the invention will be pointed out in the following disclosure and claims and illustrated in the accompanying drawings which disclose, by way of example, the principle of the invention and the presently preferred embodiments of the closure member applying that principle.

Referring to the drawings:

Fig. 1 is a plan view of the closure member;

Fig. 2 is a sectional view on the line 2—2 of

Fig. 1;

Figs. 3 and 4 are sectional views illustrating the positioning of various elements during insertion in a container;

Figs. 5 and 6 are sectional views illustrating the embodiment of the closure member adapted for use with relatively long necked bottles;

Figs. 7 and 8 are sectional views of a closure member adapted for use with wide mouthed jars; and

Fig. 9 is a sectional view of a modified closure member.

Referring to the drawings and particularly to the general utility embodiment illustrated in Figs. 1 through 4, there is provided a supporting struc-

ture including an annular plate 10 having a centrally disposed circular bore 12 having a cylindrical plug 16 slidably disposed therein. Peripherally secured to one side of the annular plate 10 is a deformable elastic sealing membrane 14. The cylindrical plug 16 is provided with extending shoulders 18 positioned intermediate the sealing membrane 14 and the underside of the annular plate 10 which limit the upward movement of the plug 16 within the bore 12. The downward movement of the plug 16 is limited by the sealing membrane 14.

Angularly disposed within the plug 16 are a pair of bores 20 and 22. The bores 20 and 22 are positioned so that they are relatively closely positioned on the upper surface of the plug 16 and relatively far apart on the lower surface of the plug 16. Slidably contained within the bores 20 and 22 are a pair of elongated retaining arms 24 and 26, respectively. The upper portions of the arms 24 and 26 are bent to provide horizontal portions 28 and 30 and suitable recesses 32 and 34 are provided on the upper surface of the plug 16 to accommodate the bent portions 28 and 30 upon maximum depression of said retaining arms 24 and 26. The lower portions of the retaining arms 24 and 26 extend through the sealing membrane 14 and are hermetically attached thereto at the points of passage 36 and 38.

Fig. 3 illustrates the positioning of the closure member in the mouth of a container 44 having a body portion 46 and a narrower neck portion 48. With the closure member placed in the mouth of the container 44, the elastic membrane 14 rests on the upper surface of the mouth of the container as illustrated in the figure.

With the parts positioned as illustrated in Fig. 3, a manual downward depression of the horizontal portions 28 and 30 results in a depression of the retaining arms 24 and 26 within the bores 20 and 22 and independent of the plug 16. The downward movement of the retaining arms 24 and 26 overcomes the restoring action of the membrane 14 which is deformed thereby. The depression of the angularly disposed retaining arms 24 and 26 causes the ends thereof positioned within the container 44 to move downwardly and outwardly until they come into contact with the sides of the container neck 48 as illustrated in Fig. 3. When the ends of the retaining arms 24 and 26 engage the sides of the container neck 48, the downward and outward movement of the retaining arms 24 and 26 independent of said plug 16 is halted.

With the ends of the retaining arms 24 and 26 in contact with the side walls of the container neck 48, a further downward depression of said arms 24 and 26 results in a downward displacement of the plug 16 together with the downward displacement of the arms 24 and 26.

The downward displacement of the plug 16, together with the retaining arms 24 and 26 then continues, against the restoring action of the membrane 14, until the ends of the said retaining arms 24 and 26 pass the end of the relatively narrow neck portion 48 of the container 44.

When the ends of the retaining arms 24 and 26 pass the end of the neck portion 48 there is no obstacle to their outward movement and a further downward depression of said retaining arms results in a further downward and outward movement thereof independent of the plug 16. Due to the angular disposition of the retaining arms 24 and 26 in the plug 16, the ends thereof disposed within the container 44 descend into the

wider body portion 46 until the bent portions 28 and 30 are disposed within the recesses 32 and 34 on the upper surface of the plug 16.

When the retaining arms 24 and 26 are in the retaining position as illustrated in Fig. 4, the elastic membrane 14 is deformed as shown in the figure. The pressure on the ends of the retaining arms 24 and 26 at the point of contact thereof with the walls of the container through the leverage obtained from the extent of said retaining arms creates a strong frictional engagement between the surfaces of said arms 24 and 26 and the surfaces of the bores 20 and 22. This frictional engagement aided in some measure by the restoring action of the elastic membrane 14 arrests any upward movement of the retaining arms 24 and 26 and the closure member is thus firmly secured in the mouth of the container.

The membrane 14 being maintained in the deformed condition and positioned as illustrated in Fig. 4, hermetically seals the mouth of the container, a sealing surface being obtained on the upper surface thereof and the vertical surface immediately adjacent thereto. The extent of the sealing surface is thus greater than that obtainable in conventional closure members.

The closure member is easily removed from retaining position in the container mouth by a slight manual depression of the plug 16. The manual depression of the plug 16 causes the retaining arms 24 and 26 contained within the angularly disposed bores 20 and 22 to move downwardly therewith. The downward movement of the retaining arms 24 and 26, together with the plug 16 relieves the pressure on the ends of the said retaining arms and the frictional engagement between said arms and said bores 20 and 22 is broken. When the frictional gripping engagement is broken, the deformed elastic membrane 14, which is secured to said retaining arms 24 and 26 at the points of passage 36 and 38, restores the retaining arms 24 and 26 to the position illustrated in Fig. 2. A release of the manual downward pressure on the plug 16 results in the upward displacement of said plug to the position illustrated in Fig. 2 through the restoring action of said membrane 14.

The above described closure member is not limited to use with a specifically sized container, as the size of the annular plate 10 may be made relatively large, permitting the use of the closure member with containers of varying mouth dimensions within predetermined limits governed by the size of said annular plate.

Figs. 5 and 6 illustrate a closure member constructed in accordance with the principles set forth above and adapted for use with bottles having relatively long necks, such as conventional carbonated beverage bottles. The elements making up this embodiment of the closure member are similar in construction and function to the embodiment illustrated in Figs. 1 through 4 and described above, and differ only in proportion as required by the different shape container with which it is to be used.

Referring to Figs. 5 and 6, there is provided a supporting structure including an annular plate 54 having a centrally disposed circular bore 56 with a cylindrical plug 58 slidably disposed therein. Peripherally secured to the annular plate 54 and extending around the plug 58 is a deformable elastic sealing membrane 60.

Angularly disposed within the plug 58 are a pair of bores 62 and 64. In this embodiment the bores are disposed side by side and are substan-

tially diagonally disposed with respect to said plug 58. Slidably contained within the bores 62 and 64 are the angularly disposed portions 70 and 72 of a pair of elongated retaining arms 66 and 68. The retaining arms 66 and 68 also include dependent substantially vertically disposed portions 74 and 76 terminating in angularly disposed container contacting portions 78 and 80.

Fig. 5 illustrates the positioning of the closure member within the mouth of a bottle 84 having a relatively long neck immediately after insertion thereof. Fig. 6 illustrates the positioning of the closure member in retaining position in said bottle 84. The operation of the closure member is similar to that for the embodiment described above with respect to Figs. 1 through 4.

Figs. 7 and 8 illustrate a closure member constructed in accordance with the principles set forth above and adapted particularly for use with wide mouth containers with varying mouth dimensions.

There is provided a supporting structure including an annular plate 90 having a centrally disposed bore 92 with a cylindrical plug 94 slidably disposed therein. Peripherally secured to the plug 94 and to the plate 90 is an annular deformable sealing membrane 96. Horizontally disposed within the plug 94 are a pair of bores 98 and 100. Slidably contained within the bores 98 and 100 are a pair of elongated retaining arms 102 and 104 having substantially vertically disposed portions 106 and 108 extending upwardly through suitable channels in the plug 94. The ends 110 and 112 of the retaining arms adapted to be disposed within a container are angularly disposed with respect to the horizontal portions 102 and 104. The horizontal portions 102 and 104 extend through an auxiliary deformable sealing membrane 114 and are hermetically attached thereto at the points of passage adjacent the end portions 110 and 112.

With the parts positioned as illustrated in Fig. 7, movement of the vertically disposed retaining arm portions 106 and 108 towards each other results in an outward displacement of the bent end portions 110 and 112 against the restoring action of the membrane 114. The outward movement of the bent portions 110 and 112 continues until said portions reach the arcuate portions 115 of the side walls of a container 116 having a relatively wide mouth. At which time a further movement of the portions 106 and 108 toward each other results in a downward depression of the plug 94 against the restoring action of the membrane 96. With the parts positioned as illustrated in Fig. 8, a tight frictional grip is provided between the horizontal portions of the retaining arms 102, 104 and the bores 98 and 100, as described above with respect to Figs. 1 through 6. This embodiment is readily removed from the container mouth by a slight manual depression of the plug 94. Breaking the frictional grip enables the deformed membrane 114 to restore the retaining arms to the position illustrated in Fig. 7.

Fig. 9 illustrates a modification of the embodiment of the invention illustrated in Figs. 1 through 4 in which one of the retaining arms 118 is fixedly mounted in the plug 120 contained within the bore 122 of the annular plate 124. The other retaining arm 126 is slidably disposed within a bore 128 within said plug 120, as described above in connection with the embodiment illustrated in Figs. 1 through 4.

Another modification illustrated in Fig. 9 is a

provision of an auxiliary sealing membrane 130 in addition to the conventional membrane 132 which is connected between the plug 120 and the annular plate 124. The operation of this embodiment of the invention is similar to that described above in conjunction with Figs. 1 through 4 and need not be repeated at this point except to note that only one of the retaining arms is manually depressable.

Having thus described my invention, I claim:

1. A closure member for a container having a body portion and a narrow neck portion, including, a supporting structure carrying a deformable sealing membrane, a pair of retaining arms guided by bores within said supporting structure and passing through and attached to said membrane, said retaining arms being manually displaceable internally of said container against the restoring action of said membrane, said bores guiding said retaining arms upon displacement thereof into closure-retaining position, said retaining arms being frictionally gripped within said bores in closure-retaining position and releasable from retaining position by manual depression of said supporting structure.

2. A closure member for a container having a narrow neck portion, including, a supporting structure carrying a deformable sealing membrane, a pair of retaining arms guided by angularly disposed bores within said supporting structure and passing through and attached to said membrane, said retaining arms being manually depressable against the restoring action of said membrane, said angularly disposed bores guiding said retaining arms upon manual depression thereof into closure-retaining position, said retaining arms being frictionally gripped within said bores in closure-retaining position and releasable from retaining position by manual depression of said supporting structure.

3. A closure for a container having a narrow neck portion, including, a supporting structure carrying a deformable sealing membrane, a pair of angularly disposed retaining arms slidably contained within said supporting structure and passing through and attached to said membrane, said retaining arms being manually depressable against the restoring action of said membrane, said retaining arms upon depression thereof past the neck portion of said container being extendible into closure-retaining position, said retaining arms in closure-retaining position being frictionally gripped within said supporting structure in closure-retaining position and releasable from retaining position by manual depression of said supporting structure.

4. A closure for a container having a narrow neck portion, including, a supporting structure carrying a deformable sealing membrane, at least one retaining arm guide by an angularly disposed bore within said supporting structure and passing through and attached to said membrane, said retaining arm being manually depressable against the restoring action of said membrane, said angularly disposed bore guiding said retaining arm upon manual depression thereof into closure-retaining position, said retaining arm being frictionally gripped within said bore in closure-retaining position and releasable from retaining position by manual depression of said supporting structure.

5. A closure for a container having a body portion and a narrow neck portion, comprising, an annular plate having a central bore, a plug axially displaceable within said bore, an elastic mem-

brane secured adjacent to the periphery of said plate, a pair of retaining arms guided by inclined bores within said plug and passing through and attached to said membrane, said retaining arms being manually depressable against the restoring action of the elastic membrane, said inclined bores guiding said retaining arms upon manual depression thereof into contact with the walls of the container neck, said retaining arms upon further depression thereof being adapted to depress the plug until the inner ends of the retaining arms pass the neck portion of the container, whereupon the retaining arms are further depressed independent of said plug into closure-retaining position, said extended retaining arms being frictionally gripped within said bores in retaining position and being releasable from retaining position by manual depression of said plug.

6. A closure for a container having a body portion and a narrow neck portion, an annular plate having a central bore, a plug axially displaceable within said bore, an elastic membrane secured adjacent to the periphery of said plate, an angularly disposed retaining arm mounted in said plug

and passing through said membrane, an angularly disposed retaining arm guided by an inclined bore within said plug and passing through and attached to said membrane, said last mentioned retaining arm being manually depressable independent of said plug against the restoring action of said membrane, said inclined bore guiding said last mentioned retaining arm upon initial manual depression thereof into contact with the walls of the container neck, said last mentioned retaining arm upon further depression thereof being adapted to depress the plug until the inner end of said retaining arm is depressed past the neck portion of the container, said last mentioned retaining arm upon further depression thereof adapted for movement independent of said plug into closure-retaining position, said last-mentioned retaining arm in closure position being frictionally gripped within said bore and releasable from retaining position by manual depression of said plug.
